UNITED STATES PATENT OFFICE.

MILLO C. MERRILL, OF FLAXTON, NORTH DAKOTA.

AUTOMOBILE SIGNAL DEVICE.

Application filed April 1, 1927. Serial No. 180,215.

My invention relates to improvements in devices for signaling from an automobile, such as a sedan, the intention of the driver to make a turn, and it consists in the combinations, constructions, and arrangements herein described and claimed.

An object of my invention is to provide a device which may be operated by vacuum action created by the engine of the automobile, and which may be controlled manually to furnish a positive means for projecting a signal into view and also a positive means for returning it to its initial position.

A further object is to provide a device of the type described which can be readily applied to automobiles, such as sedans, and which is designed to be located underneath the projecting visor of the roof of the car, where it is inconspicuous.

A further object is to provide a simple device which is positive in action and which is not liable to easily get out of order.

Other objects and advantages will appear in the following specification, and the novel features of the invention will be particularly pointed out in the appended claims.

My invention is illustrated in the accompanying drawings, forming part of this application, in which

Figure 1 is a view, partly in section, showing the manner in which the device is operated.

Figure 2 is a front view of an automobile having my improved safety signal device,

Figure 3 is an enlarged section along the line 3—3 of Figure 1, and

Figure 4 is an enlarged section along the line 4—4 of Figure 1.

In carrying out my invention, I make use of an arm 1, such as that shown in Figure 1, the end of the arm being formed in the shape of an arrowhead 2. As will be seen from Figure 4, the arm is preferably formed of

two bowed strips 3 and 4 of aluminum or similar light material, these strips being secured together at their abutting edges. On the inside of the chamber formed by these strips are disposed sheets 5, such as celluloid, colored red. Both faces of the arm have

punched or cut therefrom letters 6 to form the word "Turn" or similar legend. The metal is also cut to form an arrow 7, the purpose being to provide a signal which can be observed at night when the interior is illuminated by any suitable means not shown.

The arm 1 is connected with a slidable bar

8 having grooves 9 in its upper and lower surfaces. This bar is designed to slide in an opening 10 in a block 11, which may be made of wood or other suitable material. The block, as will be observed, has a V-shaped groove 11^a and is provided with a cover portion 12 having a groove 12^a. This cover portion may be secured to the block by means of screws 13. Balls 14 are disposed in the registering grooves, as shown in Figure 4, thus providing anti-friction means for permitting the bar 8 to slide freely.

The lower part of the block is provided with a cylindrical bore 15 in which is disposed a piston 16 having a piston rod 17 which extends through the block toward the signal. At one end of the block is a plug 18 having a packing chamber 19 therein. This plug is screwed into the end of the block, as shown, and a second plug 20 is provided by means of which the packing may be compressed about the plunger 17, which, as shown, extends through both plugs 18 and 20. The end of the plunger 17 is reduced, as shown at 21, and passes through the bore 22 of a block 23 which fits in between the sides 3 and 4. The end of the portion 21 has a nut 24 which holds the plunger to the block 23. The bar 8 is firmly secured to the block 23 so as to support the signal entirely from the bar, the bore 22 in the block 23 being of such a size as to freely admit the reduced portion 21 so that all the weight is on the bar 8 and none on the plunger rod 17 or its reduced portion 21.

In order to operate the signal, I provide a valve 25 having ports 26, 27, 28 and 29. The port 26 communicates with one end of the bore 15 by means of a pipe 30. The port 28 communicates with the opposite end of the bore 15 by means of a pipe 31, while a pipe 32 leads from the port 29 to a vacuum tank 33.

From the foregoing description of the various parts of the device, the operation thereof may be readily understood. The valve 25 is shown diagrammatically. Assuming that the signal is in the position shown in Figure 1 and that it is desired to indicate to an approaching driver the desire of the operator of the vehicle to turn, he rotates the portion 34 of the valve so as to bring the ports 28 and 29 into communication through the passage 35. The vacuum created in the vacuum tank will cause the air to enter through the port 27, passage 36

and pass by the pipe 30 to the bore 15, thus pushing the piston 16 ahead of it and causing the arm bearing the legend to be moved to the left in Figure 1, the air within the bore 15 in front of the piston being forced out through the pipe 31 and the passages 28 and 29 into the tank 33. Now in rotating the valve to bring the ports 26 and 29 into registration and the ports 27 and 28 into registration, the vacuum will be applied to the opposite end of the cylinder and the air pressure entering the port 27 will cause the reverse movement of the piston and the retraction of the signal. It will thus be seen that by merely manipulating the valve 25 the positive operation of the signal in either direction is effected. Since the bar 8 is on ball bearings, there is very little friction on the part which supports the signal, while, as stated, the weight of the signal arm is taken off from the plunger rod 17 so that there is no tendency for the signal to hang, due to friction on the plunger rod.

While I have shown the preferred form of the device as comprising a block into

which the bar 8 slides, it will be obvious that any other suitable form of casing might be used without departing from the spirit of the invention.

I claim:

1. An automobile signal comprising a casing, a bar slidably carried in the casing, a signal supported at one end of said bar, a cylinder in said casing, a piston in said cylinder, a piston rod connected with said signal, and means for causing the reciprocation of the piston to move said signal away from and toward said casing. 30

2. An automobile signal comprising a casing having an opening therein, a bar slidably disposed in said opening and movable into and out of the casing, a signal supported upon said bar exterior of the casing, a cylinder in said casing, a piston in said cylinder, a piston rod connected to said piston at one end and the signal at the other end, and means for reciprocating said piston at will, thereby moving said signal away from and toward said casing. 35 40 45
